1 Claim, 1 Drawing Sheet

The image shows a screenshot of the e-Miles website homepage. At the top, there is a header with a small airplane icon, the text "miles for minutes", and a "Memorize" button. Below the header, the user's name "Niemann" and a "Balance: 120 miles" are displayed. A navigation menu with tabs "Account", "Profile", "Member Service", and "Deposits" is visible. The main content area features a "Welcome back to e-Miles" message and a "You're now earning miles for your time with Air Lines Miles." sub-message. Below this, a section titled "New Offers" lists five items, each with a small icon, a description, an "Earn" button (containing the number "15"), and a "Remove from list" link. The offers are: 1. "Road warrior or jet setter? Tell us your travel preferences and earn miles now by completing the Travel profile." 2. "Are you a short-term or long-term investor? Call phone or land line? Earn miles now just by completing the Finances and Communications profile and telling us about your investment and communication style." 3. "From marriage to retirement, Vitamins A to Zinc, tell us how you keep healthy to enjoy life's important events. Of course, e-Miles keeps all your personal information strictly confidential." 4. "Do you enjoy high-tech electronics, waxing your car, playing fetch with Fido or redoing your home? Let us know your preferences and earn miles by completing this profile." 5. "Watch a DVD at home, or spend a night out at the movie theater? Tell us how you like to spend your free time and earn miles by completing this profile." At the bottom of the page, there are links for "View all recent opportunities" and "View my favorites". The footer contains links for "Privacy Policy", "Member Agreement", "Sponsors", and "Advertiser Information". A copyright notice at the bottom states: "© 2008-2010 e-Miles LLC.
